TUBE FINISHING MACHINE

Thomas J. Henderson, Dayton, Ohio, assignor to
 General Motors Corporation, Detroit, Mich., a
 corporation of Delaware

Application July 28, 1950, Serial No. 176,402

1 Claim. (Cl. 78—103)

1

This invention relates to improvements in machines for finishing the interior surface of tubes particularly of the formed sheet metal and welded type.

It is among the objects of the present invention to provide a machine which, by the swaging process, finishes the interior surface of a metal tube with a smooth, burnished finish.

Further objects and advantages of the present invention will be apparent from the following description, reference being had to the accompanying drawings wherein a preferred embodiment of the present invention is clearly shown.

Swaging machines as illustrated in the present drawings are purchasable in the open market and have been used for sizing and shaping metal tubes. For such operations ordinary cylindrically shaped mandrels or mandrels shaped to give finished tube the desired shape have been used. Swaging of the tube by these operations results in a matte or satin finish on the interior wall of the tube which finish is microscopically rough and uneven.

The present invention provides the ordinary swaging machine with a mandrel having alternately arranged or spaced undercut areas, such a mandrel giving the interior surface of a tube a burnished, mirror like finish instead of the matte, satin finish resulting from the use of a smooth, cylindrical mandrel.

In the drawings:

Fig. 1 is a part sectional, part diagrammatic view illustrating a standard swaging machine equipped with the present invention.

Fig. 2 is an end view of the machine shown in Fig. 1, certain parts being removed to illustrate interior features more clearly.

Fig. 3 is a schematic, full sized view of the mandrel, dies and die hammers of the machine equipped with the present invention.

Referring to the drawings, the standard swaging machine has a rotatable, hollow carrier or core 20 journaled in the housing 21. A pulley 22 is attached to the core 20, said pulley being drivingly connected to a pulley 23 by belts 24. Pulley 243 is attached to the drive shaft of motor 25 mounted upon housing 21 which has an extension providing a tubular hub in which a circular row of cammings rolls 26 are supported. The portion of the core extending coaxially into the circular space defined by rolls 26 has a diametral recess 30 in which the dies and die hammers are slidably supported. The two, oppositely disposed dies 31 and 32 have flat outer surfaces, the opposite, inner surfaces being concaved to fit

2

over and engage the tube 33 inserted into the machine for finishing purposes. Die 31 is engaged by a hammer 35 in recess 30, the outer end of said hammer having a roll 36 adapted successively to engage the rolls 26 and be moved thereby to actuate die 31 into pounding engagement with tube 33 for swaging purposes. Likewise die 32 is engaged by a hammer 37 provided with roll 38 which, like roll 36, strikes the various rolls 26 as the core 20 is rotated, thereby actuating the hammer 37 with each contact with a roll 26 to drive die 32 against the tube 33 with a swaging effect.

The feature of the present invention is the provision of a specially contoured mandrel 40 held in the core 20 of the machine, within the confines of the two, oppositely disposed dies 31 and 32, by the rod 41. When tubes of substantial length, for instance 10 to 15 feet are machined, the outer end of rod 41 is detachably and rotatably supported on any suitable standard which maintains said rod in proper position relatively to the machine.

Fig. 3 illustrates the feature elements of the present invention at substantially full size for the machining of a tube approximately one inch inside diameter. As previously described, each die 31 and 32 has a flat, exterior surface engaged by the respective hammers 35 and 37 which, like the dies are slidably supported within the diametral slot or recess 30 in the core 20. The opposite, inner surface of each die is concaved, the arcuate surface fitting about and engaging the tube 33 to be machined. The outer or entrance end of each arcuated die surface is tapered as at 43 to facilitate insertion of the tube into the annular space between the mandrel 40 and the adjacent arcuated surfaces of the dies. The dies and hammers are substantially the same length which is shorter than the overall length of the mandrel 40.

Mandrel 40 has a tapered outer end 42, the base of the tapered, or more specifically the full diameter mandrel portion, being adjacent the beginning of the tapers in the arcuated surfaces of the dies 31 and 32. The feature of the present invention resides in the provision of spaced undercut, annular areas or grooves in the surface of the mandrel 40 so that alternate areas are of different outside diameters. For purposes of this description the alternate, full diameter areas of the mandrel are indicated by A—C—E and G, the spaced undercut or smaller diameter areas being indicated by B—D and F. For machining a tube having an inside diameter of approximately 1.001 inches, mandrel areas A—C—E and G are substantially .990 inch in diameter. It will be noted

3

that the areas A and G are the extreme, outer effective mandrel areas against which the tube is hammered. The undercut or smaller diameter areas B—D and F are substantially .986 inch in diameter. Thus the larger diameter areas A—C—E and G of mandrel 40 are substantially .011 smaller in diameter than the inside of the tube 33 while the undercut areas B—D and F are .004 smaller in diameter than areas A—C—E and G and substantially .015 smaller in diameter than the inside of tube 33.

It has been conclusively proven by tests, that the smoothest and most mirror like finish is obtained when the length of all of the areas A to G inclusive vary. The variation of area lengths giving the most satisfactory results is progressively increasing the lengths of all of the areas, the shortest being adjacent the entrance end of the dies 31 and 32. The best results were obtained with a mandrel the area A of which was .6875 inch long, B, .8125 inch long, C, 1 inch long, D, 1.125 inches long, E, 1.250 inches long, F, 1.375 inches long and G, 1.5 inches long. For tubes of larger inside diameter the diameter of the mandrel must, of course, be accordingly increased, however, when the inside diameter of the tube differs from the outside diameter of the mandrel .011 inch and the undercut areas such as B—D and F are approximately .004 to .008 inch less in diameter than the adjacent larger areas such as A—C—E and G, the lengths of all areas progressively increasing as in the present instance, then completely satisfactory results are obtainable.

Fig. 1 diagrammatically illustrates dual means for moving the tube in one direction through the machine longitudinally of the mandrel therein. Each means includes two grooved wheels 50 and 51 which engage the tube, the wheel 50 being rotatably supported by any suitable bracket or standard 52 forming a part of or being attached to the machine. Wheel 51 is driven by suitable speed reducing, power transmitting mechanism driven by motor 25 or any other suitable means. The drawings schematically show this mechanism to include a bevel gear 53 attached to wheel 51 and driven by a companion gear 54 mounted on shaft 55 to which a bevel gear 56 is secured which is driven by companion gear 57 mounted on an extension rod 58 connected with the drive shaft of motor 25. A similar mechanism is provided at the front of the machine to push instead of pull the tube through the machine. Any other power transmitting mechanism or driving apparatus may be used in conjunction with the swaging machine, as long as said mechanism moves the tube through the machine at the proper speed.

When processing or interiorly finishing a tube length, the tube is inserted into the machine, 60 between dies 31 and 32 so that the tapered end 42 of the mandrel enters the tube. As the machine operates the hammers 35 and 37 will re-

4

peatedly pound said dies inwardly of core 20 toward the axis thereof. As the tube 33 enters the annular space between the opposing dies and mandrel area or portion A these hammer blows through the dies will be directed against the tube and as the tube is moved through the machine the end thereof passes over the area or portion B which is undercut. The swaging action of the machine upon the tube as it passes over area A causes displacement or flowing of metal toward the undercut area B said tube region being again subjected to swaging at the area C when the tube enters the space about said mandrel area. This action continues successively throughout the entire length of the mandrel, the repeated swaging and metal displacement or flowing process, together with the continual movement of the tube longitudinally of the mandrel as well as its many periodic rotative movements due to rotation of the tube by the contacting dies, resulting in a burnishing like action which provides the treated interior surface of the tube with an extremely smooth and mirror like finish.

Variation in the relative dimensions of cooperating elements may be made within certain limits and satisfactory results attained, however, the dimensions and arrangements here given provide for most satisfactory results.

While the embodiment of the present invention as herein disclosed, constitutes a preferred form, it is to be understood that other forms might be adopted.

What is claimed is as follows:

A burnishing mandrel consisting of a solid shaft, circular in cross-section and tapered at one end, said mandrel having alternate portions of a predetermined outside diameter and intermediate portions of a diameter predeterminately less than said alternate portions, the length of said alternate and intermediate portions progressively increasing predeterminately, starting from the portion adjacent the tapered end of the mandrel, the juncture of each of said portions presenting a substantially right angled shoulder forming a sharp annular edge at each end of said annular portion.

THOMAS J. HENDERSON.
